COOLING SYSTEM

Frank E. Rowan, Kenosha, Wis., assignor to Nash-Kelvinator Corporation, Kenosha, Wis., a corporation of Maryland

Application February 10, 1941, Serial No. 378,202

12 Claims. (Cl. 123—174)

This invention relates to cooling systems and has particular reference to the cooling system of an internal combustion motor.

Present day automobile motors are provided with a cooling jacket through which a cooling medium such as water is circulated by means of a pump. The water is passed through a radiator which is subjected to a blast of air for removing heat from the water. Present day radiators are vented directly to the atmosphere to provide for the expansion of the water due to entrained air and steam caused by the heating of the water. The vent is provided at the top of the radiator, usually in or around the filler cap. These systems are subject to the disadvantage that the repeated expansion and contraction in the volume of water causes a great deal of water to be forced out through the vent, thus reducing the supply of water in the system. When relatively expensive antifreeze solution is added to the water, this loss of cooling medium becomes expensive and is desirable to be avoided. Present day cooling systems also provide only a hydrostatic pressure head at the top of the radiator core to return the water to the circulating pump, which, during high speed operation of the motor, may not be sufficient to supply the pump with the result that a high suction is developed around the pump, causing air to leak into the system along the pump shaft and hose connection. The air thus entrained in the water causes further expansion in the volume of water and further loss through the radiator vent. The efficiency of the pump is also decreased by air in the water.

It is therefore an object of this invention to provide a cooling system which will provide positive pressure circulation throughout and which will provide for purging the air from the system without the loss of cooling medium.

It is another object of this invention to provide means for venting a positive pressure cooling system.

It is another object of this invention to provide a cooling system in which vaporized antifreeze solution will be condensed before the vapor has a chance to escape through the vent in the system.

It is another object of this invention to reduce the amount of air leaking into the cooling system.

It is another object of this invention to provide an overflow tank which will retain the expanded amount of cooling medium and return

it to the cooling system as the cooling medium contracts.

Other objects and advantages of this invention will be apparent from a consideration of the following description and claims and the attached drawings, of which there is one sheet, and in which—

Figure 1 represents a diagrammatic view of an internal combustion motor with its associated radiator and cooling system; and

Figure 2 represents a sectional view taken along a plane indicated by the line 2—2 in Figure 1 and looking in the direction of the arrows.

The motor 10 is provided with the usual type of cooling jacket through which a cooling medium is circulated by the pump 12. The pump 12 is driven from the generator shaft 14 which is in turn operated by the belt 16. The belt 16 is operated from the pulley 18 positioned on the front end of the crank shaft 20. The belt 16 also serves to operate a fan 22 for drawing air through the radiator core 24 of a radiator generally indicated at 26. The particular arrangement for driving the pump does not form a part of this invention and so is not described more fully.

Cooling medium is supplied to the pump 12 through a return pipe 28 and is forced out of the motor through a discharge pipe 30. The discharge pipe 30 is connected to an upper header 32 on the top of the radiator core 24, and the return pipe 28 is connected to the underside of a lower header 34 positioned at the bottom of the core 24.

The upper header 32 is provided with a filler spout 36 which is arranged to be closed by an air tight cap 38. This particular location of the filler spout is not material to the invention as will appear later. The lower header 34 is provided with a baffle 40 which extends completely across the width of the header 34 between the lower end of the core 24 and the outlet 41 from the header to the return pipe 28. Cooling medium entering the lower header 34 from the core 24 is forced to pass over the lip 42 at the rear edge of the baffle 40 and a trap 44 is provided along the upper surface of the lower header 34 just over the lip 42.

The trap 44 is formed by the sloping top walls 45 of the header 34 which are joined together near the center of the header. The trap 44 is connected to an overflow tank 46 positioned on top of the upper header 32 by means of a vent pipe 48 connected to the sloping walls 45 at their

junction. All of the above connections are made as air tight as possible. The overflow tank 46 is provided with a vent 50 which communicates between the overflow tank and the atmosphere surrounding the motor and radiator. If desired, the vent 50 may take the form of a filler spout if a sealable vent is provided in the upper header 32 to permit air to escape when the system is filled with the cooling medium.

In operation, the cooling system will be filled with a cooling medium such as water to the level of the top of the filler spout 36. This level corresponds to the level in the overflow tank indicated by the dotted line 52. The filler spout is then sealed by the air tight cap 38 so that there is a closed body of water from the motor 10 through the discharge pipe 30, upper header 32, core 24, lower header 34, return pipe 28 and pump 12. As the pump 12 is operated, water on the pressure side of the pump will be forced directly through the cooling system to the suction side of the pump. The hydrostatic head of water standing in the vent pipe 48 and overflow tank 46 to the level indicated at 52 will prevent water from being pumped into the tank 46. The only differential of pressure existing at the pump will be that sufficient to overcome the friction losses of the cooling medium in passing through the system, thus very little air will leak into the system around the pump 12 along the shaft 14 and the hose connections.

As the cooling medium passes from the relatively constricted core 24 to the broad passage over the baffle 42, it is slowed up in passing under the trap 44 due to the increased area through which it has to flow. Any air which has been entrained in the cooling medium will have ample opportunity to rise as bubbles into the trap 44 from where it will rise through the pipe 48 to the vented overflow tank 52. Entrained air is thus purged from the cooling system.

Should the volume of the cooling medium expand, the excess volume will be forced up the pipe 48 to the overflow tank 46, which has capacity for retaining the increased volume of cooling medium. The size of the overflow tank may easily be determined to provide sufficient capacity over the level 52 by considering the volume of cooling medium in the system and the co-efficient of expansion and temperature range of the medium. Attention is called to the fact that since the system will take in less air than the older type of cooling system and since most of the entrained air will be exhausted through the pipe 48, the present cooling system will not be subject to as much expansion of the cooling medium as in the older systems. The pump 12 will also operate more efficiently due to the lack of air in the system. Upon contraction of the volume of the cooling medium, that portion of the cooling medium stored in the tank 46 above the level 52 will return through the pipe 48 to the lower header 34. Since the only place for air to return to the cooling system with the contracting cooling medium is through the vent 50 and pipe 48, it should be evident that no air will enter the cooling system until the level of the cooling medium has fallen sufficiently to create a vacuum in the system which is strong enough to draw air through the column of water in the pipe 48. The cooling system thus prevents air from entering the system through the vent and by leakage around the pump and thus reduces the amount of expansion of the body of the cooling medium.

When the cooling system is filled with anti-freeze solution, which generally has a lower boiling point than water, any vapors caused by boiling of the anti-freeze solution will be forced first through the sealed upper header 32 and core 24 where they will be at least partially condensed by the cooling action of the air stream passing through the core before they are passed underneath the trap 44. Since the trap 44 forms the only passage for the escape of vapors from the system, the loss of anti-freeze solution due to boiling of the solution is materially decreased.

The system provides all of the advantages of a sealed cooling system while retaining a constantly open vent as a safety factor. The system is operable with cross flow radiators as well as with the conventional vertical flow radiator illustrated. The more or less diagrammatic disclosure of the system is to be taken as an example only and not as a limitation of my invention, to which I make the following claims.

I claim:

1. A cooling system for an internal combustion motor comprising a closed circulating system, a radiator in said system, a lower header for said radiator having an inlet and outlet, a baffle in said header positioned between said inlet and outlet, a trap positioned over said baffle, and a vent pipe opening into said trap and extending to a point above said cooling system.

2. A cooling system for an internal combustion motor comprising a closed circulating system, a radiator in said system, a lower header for said radiator having an inlet and outlet, a baffle in said header positioned between said inlet and outlet, a trap positioned over said baffle, and a vent pipe opening into said trap and extending to a point above said cooling system, said baffle being arranged to reduce the speed of the cooling medium circulating in said system as the medium passes underneath said trap.

3. A cooling system for an internal combustion motor comprising a closed circulating system, a radiator in said system, a lower header for said radiator having an inlet and outlet, an overflow tank positioned above said circulating system, and a vent pipe communicating between said lower header and said overflow tank, said overflow tank being vented to the atmosphere.

4. A cooling system for an internal combustion motor comprising a closed circulating system, means forming a relatively constricted passage at a lower portion of said circulating system, means forming a relatively broad passage adjacent to said constricted passage, a trap positioned over said broad passage, and a vent pipe communicating between said trap and the atmosphere surrounding said circulating system at a point above the level of said circulating system, said circulating system being arranged to pass a cooling medium first through said constricted passage and then through said broad passage.

5. A cooling system for an internal combustion motor comprising a sealed upper header, a core connected to the underside of said upper header, a lower header connected to the bottom of said core and having a top wall unobstructed by said core, said top wall sloping upwardly to the center of said lower header to form a trap, a baffle positioned in said lower header underneath said core and having a lip positioned underneath said trap, an outlet for said lower header positioned underneath said baffle, an overflow

tank positioned on top of said upper header, and a vent pipe communicating between said trap and said overflow tank.

6. A cooling system for an internal combustion motor comprising a sealed upper header, a core connected to the underside of said upper header, a lower header connected to the bottom of said core, said top wall sloping upwardly to the center of said lower header to form a trap, a baffle positioned in said lower header underneath said core and having a lip positioned underneath said trap, an outlet for said lower header positioned underneath said baffle, an overflow tank positioned on top of said upper header, a vent pipe communicating between said trap and said overflow tank, and means forming a closable opening for filling said system with a cooling medium.

7. A cooling system for an internal combustion motor comprising a pair of headers, a core extending between said headers, a pipe for delivering a coolant from said motor to the upper of said headers, a second pipe for delivering coolant from the other of said headers to said motor, an overflow tank positioned above said upper header, a vent pipe connected between a point near the lower level of said system and said overflow tank, said overflow tank defining a constantly open aperture communicating with the atmosphere about said system and a pump for circulating coolant in said system.

8. A cooling system for an internal combustion motor comprising a pair of closed headers, a core extending between said headers, a pipe for delivering a coolant from said motor to the top of one of said headers, a second pipe for delivering coolant from the bottom of the other of said headers to said motor, an overflow tank positioned above said first pipe, means forming a trap in said system between said core and said other pipe, a vent pipe connected between said trap and said overflow tank, and a pump for circulating coolant through said system.

9. A cooling system for an internal combustion motor comprising a pair of headers, a core extending between said headers, a pipe for delivering a coolant from said motor to the top of one of said headers, a second pipe for delivering coolant from the bottom of the other of said

headers to said motor, means in said other header defining a passage of enlarged area through which the coolant must flow, a vent pipe communicating with said other header above said means, an overflow tank positioned above said first pipe, said tank being vented to the atmosphere around said system and connected to said vent pipe, and a pump for circulating coolant in said system.

- 10. 10. A cooling system for an internal combustion motor comprising a pair of headers, a core extending between said headers, a sealable filling spout connected to the top of one of said headers, a pipe for delivering a coolant from the motor to the top of one of said headers, a second pipe for delivering coolant from the bottom of the other of said headers to said motor, a baffle positioned in said other of said headers between said core and said second pipe, an overflow tank positioned above said first pipe, a vent pipe communicating between said overflow tank and said other header at a point just above said baffle, and a pump for circulating coolant through said system.
- 15. 11. A cooling system for an internal combustion motor comprising a cooling jacket, a radiator, a fluid impeller, means connecting said jacket, radiator and impeller in a closed circuit, sealable means for admitting a cooling fluid at the top of said circuit, an air trap interposed in said circuit at a point below the upper level thereof and over the path of flow of the cooling fluid at that point, and means forming a vent extending from said air trap to a point above the upper level of said circuit.
- 20. 12. A cooling system for an internal combustion motor comprising a cooling jacket, a radiator, a fluid impeller, means connecting said jacket, radiator and impeller in a closed circuit, sealable means for admitting a cooling fluid at the top of said circuit, an air trap interposed in said circuit at a point below the upper level thereof, and means forming a vent extending from said air trap to a point above the upper level of said circuit.
- 25. 40. 45. 45. of said circuit, said last mentioned means forming an overflow tank above the upper level of said circuit.

FRANK E. ROWAN.
